(57) **CLAIM**

The ornamental design for a portion of headgear, as shown and described.

DESCRIPTION

FIG. 1 is a perspective view of a portion of headgear for use with a respiratory mask;

FIG. 2 is a front view thereof; and,

FIG. 3 is a rear view thereof.

A portion of headgear shown in FIG. 1-3 is shown in its pre-use condition. A portion of headgear is designed to wrap about the head of a patient in use.

Where included, broken lines showing environment or structure are for illustrative purposes only and form no part of the claimed design.
